UNITED STATES PATENT OFFICE.

CHRISTOPHER J. LAKE, OF BRIDGEPORT, CONNECTICUT.

HYDROPLANE, ALSO APPLICABLE TO HYDROAEROPLANES.

1,307,135.

Specification of Letters Patent. Patented June 17, 1919.

Application filed September 17, 1917. Serial No. 191,712.

To all whom it may concern:

Be it known that I, CHRISTOPHER J. LAKE, a citizen of the United States, and resident of Bridgeport, in the county of Fairfield and

5 State of Connecticut, have invented certain new and useful Improvements in Hydroplanes, also Applicable to Hydroaeroplanes, of which the following is a specification.

10 This invention relates to means of flotation for vessels, such as hydroplanes, either when used as water craft alone, or when forming the base support for the type of aircraft known as hydroaeroplanes or seaplanes.

15 The float member which is the basis of my improvements, is a development of the corresponding float included in my earlier patents Nos. 913515 and 1,041,489, which were so devised as to permit the introduction 20 of a layer of elastic fluid between the float and the body of supporting water, to serve as a friction reducing medium.

The leading characteristics of my said improvements may be summarized as:—

25 (1) The float is so constructed as to present to the water surface an entrapped strata of elastic fluid upon which it is supported while either at rest or in motion. This strata of elastic fluid may be either air, 30 or mingled air and exhaust products from a propelling motor. Whether the float be a hydroplane or the base support of a hydroaeroplane, the principles governing its employment with relation to a supporting body 35 of water are substantially the same, with the addition, in the case of a hydroaeroplane, that certain inherent advantages accrue therein through the coördinated arrangement of the float and the supporting unit.

40 (2) Thus the float, which may be deeply immersed in the body of supporting water, may rise out of the water at an ascending angle, whereby the supporting unit, whose angle of incidence is set to present the least 45 resistance to the wind while afloat, will become angled to a point where the hydroaeroplane may the most readily rise from the surface of the water.

(3) The float may lie high upon the 50 surface of the water, over a maximum depth of intervening elastic fluid; but when, as in the case of a hydroplane, floating at rest in the presence of heavy winds, or rough seas, it is

desirable to immerse the float more deeply, I am enabled to lower it in the body of water 55 by exhausting some of the entrapped elastic fluid.

Thus, variability in the depth of immersion of the float is attained and may be placed within the control of the operator. 60

(4) My improved float, which resembles an inverted vessel, is provided at its open base with a succession of transverse, longitudinally arranged, spaced aquafoils, which exercise various functions, viz: of enabling the 65 float, under headway, to rise readily toward the surface from its point of submergence; to leave the surface with a minimum of drag; and, to exercise an entraining or siphoning action with respect to the interior of 70 the float; whereby, under the condition of the motor exhaust opening into said float, the suction created by the water passing said aquafoils is diminished.

(5) By reason of the entrapping character 75 of the float, a hydroaeroplane with such a float will, when alighting on water, tend to further compress the entrapped elastic fluid which thus offers yielding resistance, and, to a certain extent, cushions the impact of 80 the float upon the water.

Other features and advantages of my invention will hereinafter appear.

In the drawing:—

Figure 1 is an elevation of a hydroaero- 85 plane having my improvements.

Fig. 2 is a front elevation of the same.

Fig. 3 is a side sectional view of the float.

Fig. 4 is a cross sectional view of the same.

Fig. 5 is a top plan view, and 90

Fig. 6 is a bottom plan view.

In the drawing I have illustrated my improved float as forming part of an "aquaïrplane" or hydroaeroplane, but I am aware that the fundamental principles of invention involved in the construction and controlling agencies of said float are also applicable therewith when it is employed as a boat for travel only upon water in the manner of a hydroplane. 95

The said improved float consists of a deck portion 1, sides 2 and 3, and end portions 4 and 5. Thus constituted, the float represents an inverted vessel. Its end portions 4 and 5, respectively forming the bow and 105 stern, may comprise hollow, airtight com-

partments, containing air, or some buoyant material, and they may have sufficient buoyancy to prevent the structure from sinking.

Extending transversely across the float, 5 at the bottom thereof, is a series of aquafoils 6, separated from each other by spaces 7, and whose forward portions are upwardly inclined. The aquafoils extend longitudinally, in overlapping arrangement through- 10 out the length of the otherwise open bottom of the float, following its lower contour. This conformation, which under the bow portion is of the nature of a hydroplane angle or curve, inclines upwardly toward the 15 stern, for a purpose to be described herein-after.

The aquafoils also possess the function, particularly when the float is deeply immersed, of affording an anchorage or pur- 20 chase which tends to prevent a rolling or pitching action of the float.

The float is shown as supporting a fuselage 8 by struts 9, and aerofoils representing a supporting unit are indicated at 10. A pro- 25 pelling motor is also indicated, at 11, because the exhaust therefrom may be utilized in the performance of my invention. Auxiliary thereto will be noted air pipe 12, opening into the interior of the float, and having 30 check valve 13; this air pipe also serving as a duct to convey exhaust gases from the motor to the float interior, for which purpose air pipe 12 is caused to represent the exhaust manifold.

35 The check valve 13 may be automatic in action, *i. e.*—caused to open by the outward flow of exhaust gases, and held open thereby, said check valve closing under the compression pressure of the entrapped air and gases 40 with the impact force of the hydroaeroplane alighting upon the water surface, thereby preventing flooding of the motor.

It will be apparent that, when the hydro- 45 aeroplane alights upon the water, the air and gases within the float will become compressed toward the deck portion thereof, so that the impact will have a somewhat yielding character, and thus tend to lessen the shock of landing by affording a pneumatic 50 cushion.

When at rest upon the water the deck line of the float is substantially parallel with the surface. I preferably arrange the incidence of the supporting unit relatively to said deck 55 line, so that it is at a neutral angle. Thus, while the hydroaeroplane is at rest, or floating on water, the drift potentiality is at a minimum. This condition is desirable, to prevent dragging of anchorage, etc. Usu- 60 ally the supporting unit of a hydroaeroplane, when floating, presents an angle of incidence in the line of flight, to facilitate leaving the water, but the particular design and characteristics of my float are intended 65 to obviate this necessity. For example, when

propulsive power is applied, and forward travel of the hydroaeroplane occurs, support being mainly upon a strata of air, which, with the operation of the motor is augmented by the admixture of exhaust gases, the 70 aquafoils, due to their shape, and the upward inclination of their line toward the stern, will pivot the float to turn the bow portion upwardly, thereby increasing the attacking angle of the supporting unit, until 75 the speed pressure becomes sufficient for ascent. It will be evident, from a consideration of my earlier patents, herein referred to, that the layer of air and gases, continuously provided with the operation of the 80 motor, and which, issuing from the spaces separating the aquafoils, will roll between the under surfaces thereof and the supporting water, constitutes an anti-frictional bearing which greatly facilitates travel of the 85 float both through and upon the surface of the supporting water; also, in conjunction with the upwardly inclined sternward line, tending to prevent drag of the float in leaving the water. It will also be noted that, 90 while traveling upon the water, the aquafoils assist, by entrainment, under the influence of suction created by the passing water, to siphon the elastic fluid outwardly through the spaces which separate said 9. aquafoils. Furthermore, it will be appreciated, that when the hydroaeroplane is in flight through the air, a corresponding entraining action will ensue between the aquafoils and supporting pressures, supplemented 100 of course by the exhaust pressures, and the resulting diminution in frictional resistance, in this instance, will be measurable because of the relatively lighter density of the elastic fluid which is thus introduced between the 105 aquafoils and the air pressures.

It is to be noted that the overlapping spaced relation indicated between succeeding aquafoils, has the result of directing rearwardly the expulsion of elastic fluid from 110 the float, whereby, through impingement against the supporting medium a degree of propulsive effect is obtained.

Recurring to the floating condition of the device, when it is supported upon the body 115 of water by a layer of compressed air within the float, sealed therein by the water, I provide for varying the degree of immerge- 120 nce or submergence of the float by means of a relief valve, as 14, which may be entered in the deck 1, and operable by suitable known means. Through this valve such portions of the contained elastic fluid may be released as will enable the float to settle to a desired depth in the water, as at times when the water is rough, with the hydroaeroplane either at anchor or in motion, and when on account of the wave actions, the float must seek a greater depth at which to secure the water seal.

The term aquafoils used by me to designate the leaves which constitute the transverse members 6 as the bottom of the float may be equally expressed by the abbreviation foils which I employ in referring to said members in the claims.

While I have inferred herein the use of an internal combustion motor as the means of supplying the elastic fluid to the float interior, I do not wish to be limited thereby, realizing that other known means may be employed for the same purpose.

Variations may be resorted to within the spirit and scope of my invention, and parts thereof used without others.

I claim:—

1. A float comprising an inverted vessel having a series of longitudinally arranged transverse foils along its base, said foils separated by exteriorly communicating spaces, and said float presenting contained elastic fluid for compression, to provide buoyant support for said float.

2. A float having buoyant bow and stern portions, an intermediate means for presenting co-extensively therewith an undivided body of elastic fluid as a unitary element to entrapping and supporting compression by a contacting body of water.

3. A float having buoyant bow and stern portions, intermediate means for presenting a body of elastic fluid to entrapping compression by a contacting body of water, and means for diminishing the volume of the entrapped elastic fluid, to increase the immersion depth of said float.

4. The combination, in a float, of means for presenting an undivided body of elastic fluid, co-extensively with said float bottom, as a unitary element to entrapping compression by a body of water, for the support of said float.

5. The combination, in a float, of means for presenting a body of elastic fluid to entrapping compression by a contacting body of water, for the support of said float, and means for diminishing the volume of the entrapped elastic fluid, to increase the immersion depth of said float.

6. The combination, in a hydroplane, of means for presenting an undivided body of elastic fluid to entrapping compression by a body of water, for the support of said hydroplane, a series of foils longitudinally spaced along the base line of said hydroplane, under which said elastic fluid entrains in the travel of said hydroplane, and means for replenishing the supply of elastic fluid.

7. The combination, in a hydroaeroplane, of a float for its support on water, an aerofoil for its support in air, said aerofoil having a set neutral angle of incidence relatively to said float, a motor, means for communicating the exhaust gases from said motor to the interior of said float, and means

for the discharge of said gases by combined pressure and entraining action, in motion, from the base of said float.

8. The combination, in a hydroplane, of means for presenting entrapped elastic fluid to compression by a body of water for the support of said hydroplane, and a series of foils longitudinally spaced along the base line of said hydroplane, said foils serving, when the hydroplane is deeply immersed, to secure it against rolling and pitching.

9. The combination, in a hydroplane, of means for presenting an undivided body of elastic fluid to entrapping compression by a body of water for the support of said hydroplane, and a series of foils longitudinally spaced along the base line of said hydroplane, the contour line of said series of foils having an upwardly rearward inclination, to assist in imparting a forward rising angle to said hydroplane, under headway.

10. The combination in a hydroplane comprising an inverted vessel, of a series of foils longitudinally spaced along the base line thereof, a motor, and means for communicating the exhaust gases from said motor to the interior of said vessel, the pressure of said gases causing their efflux between said foils, and, in motion of the hydroplane, their passage between said foils and the supporting water.

11. The combination, in a hydroaeroplane having a motor, of a float therefor comprising an inverted vessel, means for communicating exhaust gases from said motor to the interior of said vessel, and a check valve operating under the impact pressure of the float in alighting upon a body of water, to close said communicating means and thereby prevent flooding of the motor.

12. The combination with a hollow float, of a succession of transverse foils comprising the bottom thereof, said foils separated by intervening spaces, a motor, and means for discharging exhaust gases from said motor into said float, for efflux through said spaces and passage between said foils and a supporting fluid body.

13. In combination, a hollow float in the form of an inverted vessel, open at and co-extensively with its base, a motor, and means for discharging exhaust gases from said motor into said float, for efflux between said float and a supporting fluid body.

14. The combination with a hollow float in the form of an inverted vessel, open at and co-extensively with its base, a motor, and means for discharging exhaust gases into said float, of means for directing the efflux of said gases rearwardly between said float and a supporting fluid body, for propulsive effect.

15. The combination with a hollow float, of a succession of transverse foils comprising the bottom thereof, said foils separated

by intervening spaces, a motor, and means for discharging exhaust gases from said motor into said float, said foils directing the efflux of said gases with propulsive effect 5 through said spaces against a supporting fluid body.

Signed at Bridgeport, in the county of

Fairfield and State of Connecticut, this 12th day of September, A. D. 1917.

CHRISTOPHER J. LAKE.
